Primary Examiner—Terry A. Wallace
Attorney, Agent, or Firm—Hoffmann & Baron, LLP[57] **CLAIM**

The ornamental design of a spoon/straw combination, as shown and described.

DESCRIPTION

FIG. 1 is a perspective view of a spoon/straw combination showing my new design;

FIG. 2 is a right side elevation view thereof, the left side being a mirror image thereof;

FIG. 3 is a top plan view thereof;

FIG. 4 is a bottom plan view thereof;

FIG. 5 is a front elevation view thereof; and,

FIG. 6 is a rear elevation view thereof.

The phantom line illustration of the novelty figure attached to the spoon/straw combination, which appears in each of the drawing figures, is for reference only and forms no part of the claimed ornamental design.
